CLAIM

The ornamental design for a pocket knife, as shown and described.

DESCRIPTION

FIG. 1 is a perspective view of the pocket knife;

FIG. 2 is a top view of the pocket knife;

FIG. 3 is a bottom view of the pocket knife;

FIG. 4 is a left side view of the pocket knife;

FIG. 5 is a right side view of the pocket knife;

FIG. 6 is a back view of the pocket knife; and,

FIG. 7 is a front view of the pocket knife.

The broken lines depict portions of the pocket knife in which the design is embodied that are not considered part of the claimed design.

1 Claim, 4 Drawing Sheets(56)
